UNITED STATES PATENT OFFICE.

CHARLES R. EDWARDS, OF HOUSTON, TEXAS.

ROTATING JAR.

Application filed March 13, 1922. Serial No. 543,252.

To all whom it may concern:

Be it known that I, CHARLES B. EDWARDS, citizen of the United States, residing at Houston, in the county of Harris and State of Texas, have invented certain new and useful Improvements in a Rotating Jar, of which the following is a specification.

This invention relates to new and useful improvements in a rotating jar.

- 10 One object of the invention is to provide a device of the character described which has been designed for use in well drilling with cable tools, and more particularly for the purpose of unscrewing and withdrawing 15 pipe or other parts of the drilling apparatus which may become stuck in the well bore. In the process of drilling wells the pipe or drilling tools sometimes become stuck in the well bore and cannot be pulled out and it becomes 20 necessary to unscrew the joints of pipe, or other parts of the drilling appliances so struck and withdraw them a joint, or part, at a time. It is the object of this invention to provide a rotating jar which 25 may be connected to the parts to be withdrawn, and by means of which they may be unscrewed and separated and thus removed from the bore.

Another object of the invention is to provide 30 a rotating jar which may be released and withdrawn from the bore, in case the pipe or other drilling apparatus in the bore is so tightly stuck that it cannot be recovered.

35 A still further feature of the invention resides in the provision of a rotating jar which is of simple construction and may be cheaply and easily manufactured and which may be effectively operated by the appliances at hand in cable tool drilling.

With the above and other objects in view the invention has particular relation to certain novel features of construction, operation and arrangement of parts, an example 45 of which is given in this specification and illustrated in the accompanying drawings, wherein:—

Figure 1 is a vertical sectional view of the complete device and,

50 Figure 2 is an enlarged vertical sectional view of the lower part thereof.

Referring now more particularly to the drawings, the numeral 1 designates the cable by means of which the device is suspended in the bore. The upper end of this cable is attached to a suitable working beam at the

ground surface, this working beam has not been shown for the reason that it is in common use and its construction is well known to those skilled in the art of cable tool drilling. Fastened to the lower end of this cable there is a clamp 2 provided with a depending spindle 3 which carries the swivel 4. This swivel is threaded into the upper end of a tubular weight 5 in which 5 there is threaded or otherwise secured the cylindrical hammer 6 which is considerably shorter than the weight 5 and located approximately midway between the ends thereof. The numeral 7 designates the part which is stuck in the bore and which is sought to be withdrawn. The hammer 6 has a vertical central passageway 8 whose respective ends are blank and intermediate said blank ends the opening is provided with coarse threads which are preferably mutilated. Threaded through the opening 8 there is a rod 9 which has a coarse external thread of considerable pitch and which intermeshes with the threads of the hammer. The upper end of the rod 9 has a head 10 fixed thereto and the lower end thereof carries the internally threaded socket member 11. Depending from the socket member there is a grappling member 12 whose lower end is formed to engage with the pipe or other part to be pulled. As shown this grappling member is in the form of an external die adapted to be threaded over the upper end of the pipe, but any other type of grappling member may be employed.

For illustration it is assumed that the joints of the pipe to be removed are connected by right hand threads. The threads of the grappling member 12 will accordingly be left handed. In operation the device is let down into the bore and the die of the grappling member will engage over the upper end of the pipe to be pulled. The weight 5 is then alternately elevated and suddenly dropped. During this operation the rod 9 will remain stationary the weight of it and its appendants being sufficient to hold it in a stationary position. When the weight is dropped it is obvious that it will whirl, in a left handed, or anticlockwise direction and when the hammer strikes the upper end of the socket member its rotation will be imparted to said socket member causing a partial rotation thereof in a left hand direction and the die will gradually cut threads on the upper end of the pipe to be removed until it securely engages therewith and as succeed-

ing strokes of the hammer are delivered to said socket member, the upper joint of pipe to be removed will be gradually unscrewed from the joints beneath it and can be lifted 5 out and removed.

In case the joints of pipe are so securely stuck together that they can not be unscrewed it will become necessary to release the tool from the stuck pipe so that it can 10 be withdrawn from the bore. In order to release, or back off the tool from the pipe 7, the operation is reversed, that is the weight is pulled upward suddenly, in successive strokes and as it moves upwardly on the rod 15 5 it will rapidly rotate toward the right and the hammer 6 will strike the head 10 with successive strokes. Each stroke will impart a partial rotation toward the right to the head 10 and, through the rod 9, to the 20 tool 12 gradually unscrewing the grapping tool 12 from the pipe so that the device may be withdrawn from the bore.

It is to be noted that the upper end of the 25 socket member 11 is formed with oppositely disposed shoulders 13, 13 and the lower end of the hammer is formed with corresponding shoulders as 14 which abut against the shoulders 13 when the hammer is dropped thus increasing the friction and insuring the 30 rotation of the socket member 11 through the strokes delivered to it by the hammer, and likewise the lower end of the head 10 has shoulders 15 against which the shoulders 16 35 carried by the upper end of the hammer contact to insure the rotation of said head and the rod 9 from the successive hammer strokes.

What I claim is:—

1. A device of the character described including an engaging member, a rotary hammer and means connected to said member against which the hammer strikes to impart successive partial rotations thereto with successive strokes.

2. A device of the character described including a member adapted to engage with pipe and the like, a rotary hammer, and means connected to said member against which said hammer is adapted to strike to 50 rotate said member.

3. A device of the character described including a member adapted to engage with pipe and the like, a hammer vertically movable relative to said member, means for reciprocating said hammer up and down, means for rotating the hammer as it moves

up or down, and abutments carried by said member on opposite sides of said hammer against either of which the hammer is adapted to strike.

60

4. A device of the character described including a pipe engaging member, a reciprocating hammer, means for rotating the hammer as it reciprocates, abutments connected to the member one on each side of the hammer, against either of which the hammer is adapted to strike.

65

5. A device of the character described including a tool formed to engage with pipe and the like, a reciprocating hammer, means for rotating the hammer as it reciprocates, abutments connected to the tool one on each side of the hammer against one of which the hammer is adapted to strike to rotate the tool in one direction and against the other of which the hammer is adapted to strike to rotate the tool in the other direction.

70

6. A device of the character described including a rotary tool, a coarsely threaded rod upstanding from said tool, a hammer reciprocable on said rod to which rotation is imparted by the threads thereof as it reciprocates, and an abutment carried by said rod on each side of said hammer.

75

7. The combination with a rotatable tool of a threaded part connected thereto, a member reciprocable relative to said threaded part and to which rotation is imparted by said threads as it reciprocates.

80

8. The combination with a rotatable tool of a threaded part connected thereto, a member reciprocable relative to said threaded part and to which rotation is imparted by said threads as it reciprocates, and an abutment connected to said tool against which the reciprocating member is adapted to strike.

85

9. The combination with a rotatable tool of a threaded part connected thereto, a member reciprocable relative to said threaded part and to which rotation is imparted by said threads as it reciprocates, and abutments connected to said threaded part on opposite sides of the hammer.

90

In testimony whereof I have signed my name to this specification in the presence of two subscribing witnesses.
